UNITED STATES PATENT OFFICE

149,573

DESIGN FOR A LOCOMOTIVE BODY

Raymond Loewy, New York, N. Y., assignor to
Fairbanks, Morse & Co., Chicago, Ill., a cor-
poration of Illinois

Application October 5, 1946, Serial No. 133,799

Term of patent 14 years

(Cl. D66—1)

To all whom it may concern:

Be it known that I, Raymond Loewy, a citizen
of the United States, residing at 580 Fifth Ave.,
New York, in the county of New York and State
of New York, have invented a new, original, and
ornamental Design for a Locomotive Body, of
which the following is a specification, reference
being had to the accompanying drawing, forming
part thereof.

In the drawing:

Fig. 1 is a view in side elevation of a locomotive
body, showing my new design;

Fig. 2 is a top plan view of the design;

Fig. 3 is an end elevation of the cab end, at the
left as viewed in Fig. 1, and

Fig. 4 is an end elevation of the opposite end
of the locomotive body.

Fig. 5 is a side perspective view of the locomotive
body.

The opposite side elevational view of the locomotive
body is substantially identical with the
view of Fig. 1.

The dotted line showing in Figs. 1, 3, 4 and 5
is for illustrative purposes only.

I claim:

The ornamental design for a locomotive body,
as shown and described.

RAYMOND LOEWY.
